DESIGN FOR A GOLF CLUB HEAD

James Harold Flowers, Port Arthur, Tex.

Application September 16, 1940, Serial No. 95,124

Term of patent 7 years

To all whom it may concern

Be it known that I, James Harold Flowers, a citizen of the United States, residing at Port Arthur, in the county of Jefferson and State of Texas, have invented a new, original, and ornamental Design for a Golf Club Head, of which the following is a specification, reference being had to the accompanying drawing, forming a part thereof.

In the accompanying drawing,

Figure 4 is an end view looking toward the toe of the club head;

I claim:

The ornamental design for a golf club head, as shown.

JAMES HAROLD FLOWERS.
